UNITED STATES PATENT OFFICE

2,075,924

MACHINE FOR OPERATING UPON SHOE SOLES

Charles Martin Bagshaw, Leicester, England,
assignor to United Shoe Machinery Corporation,
Paterson, N. J., a corporation of New Jersey

Original application July 7, 1934, Serial No.
734,129. Divided and this application March
5, 1936, Serial No. 67,342. In Great Britain
July 29, 1933

18 Claims. (Cl. 12—18)

My invention relates to machines for operating upon the soles of shoes, it being especially applicable to apparatus by which rounding and channeling operations are performed.

5 In an application for Letters Patent of the United States for improvements in Methods of and machines for operating upon shoe-soles, filed in my name in the United States Patent Office on July 7, 1934, the serial number being 10 734,129, and of which the present application is a division, is disclosed a novel method of producing about the forepart of soles what is known as an English channel and at the opposite sides of the waist or shank, an American channel. This 15 American channel is formed by first cutting an English channel at the waist in connection with the operation upon the forepart, and thereafter deepening and widening the channel and rounding away a portion of the sole-margin until said 20 channel opens through the edge of the sole instead of through the tread-surface. The first, or English-channeling operation, may be performed by an apparatus of the character of that which is the subject of Letters Patent of the 25 United States No. 1,030,606, Perry, June 25, 1912. The transformation of this English channel at the waist-portion of a sole into an American channel may be by a modification of the machine of the Perry patent. It is an object of my invention to arrange, in such an apparatus, for the correct presentation of the previously channelled sole to the instrumentalities which are to further operate upon it. To this end, I cause the sole to be gripped, as between a feed-plate 30 and a sole-support, in the desired relation to a channeling knife, the position of the work being determined by a crease-guide. Said work is then allowed, through movement of the guide, to be raised into operating position to receive the action of the channeling knife and of a rounding knife. The former knife, lowered for the engagement, will increase the depth of the already cut channel and will widen the opening to give, when the channel is closed, a thinner sole-edge, 35 while the latter knife, by narrowing the sole-margin, causes the emergence of the channel through the sole-edge. Sequential operation of the elements is preferably attained by a single member actuated by the operator, there being 40 illustrated herein for this purpose a treadle-rod. This rod, acting through a second rod and connecting lever, first effects the clamping of the work to be presented to the elevated channeling knife and temporarily maintained out of operating 45 position by the crease-guide, and then raises 50

the guide and lowers the channeling knife, the location of the guide permitting the work to assume a position in which both the rounding knife and channeling knife may operate.

In the accompanying drawings is shown a particular embodiment of my invention, 5

Fig. 1 being a broken side elevation, partly in section, of my improved machine;

Fig. 2, a front elevation of the treadle-rod-connecting mechanism;

Fig. 3, a front elevation of the parts of the machine more closely co-operating with the work;

Fig. 4, an enlarged side elevation of the parts of the machine appearing in Fig. 3 and in the 10 positions they occupy as the work is presented;

Fig. 5, a view similar to Fig. 4, showing the 15 elements as they operate upon the work;

Fig. 6, a transverse, sectional detail taken at the waist of a shoe, this representing the condition of the work when it comes to the machine 20 of my invention, and

Fig. 7, a view similar to Fig. 6, but showing the condition of the work after the machine has 25 operated upon it.

As already indicated, my improved machine may be of the general character of that disclosed in the Perry patent. This machine comprises a reciprocating rounding or trimming knife

30 39, a block or sole-support 41, an oscillating channeling knife 43 carried by the sole-support, a feed-plate 45, a crease-guide 47 and a sticker-point 49. No forepart-guide is necessary. The

machine is provided with two treadle-rods 51 and 53, respectively, for controlling the retraction of the sole-support 41 from the feed-plate 35 45 and for controlling the heightwise level of the sole-support 41 and of the crease-guide 47 with respect to the rounding knife 39. In the present

machine, only one treadle (not shown) is provided. This is attached to the rod 53, and the rod 51 is connected with the rod 53 in order that

the single treadle may operate both. Pivoted to the lower end of the rod 51 is a lever 55, which 40

lever is fulcrumed at 57 on the column 59 of the machine. The left-hand end of the lever 55

(Fig. 2) is forked to embrace the rod 53, and, just above the forked end of the lever, this rod has a collar 61 secured upon it. The arrangement is such that depression of the treadle will 45

cause the lowering of the rod 53 and, through the lever 55, elevation of the rod 51. In usual

fashion, the upper end of the rod 51 is in connection with one arm 63 of a bell-crank-lever, another arm of which is formed as a depending 50

55

hand-lever 65. The bell-crank-lever is secured to a rock-shaft 67, which also has fast upon it an arm 69 arranged to engage a lug 71 upon a sleeve 73. This sleeve is secured upon a shaft 75, which has a support 77 fixed at its forward end. The support 77 has mounted upon it a carrier-slide 79 on which the sole-support 41 is arranged for limited rocking movement in an arcuate guideway 81. The extent of rocking movement is limited by a pin 83 (Figs. 4 and 5) in the slide entering a slot 85 in the sole-support. The shaft 75 is capable of sliding axially in its bearing to move the sole-support toward and from the feed-plate 45, and a spring 87 engaging its rear end tends to urge the shaft forwardly. The maximum permitted forward movement of the shaft 75 is limited by the engagement of a flange 89 upon the sleeve 73 with the front bearing 91 for the sleeve and the shaft 75. The shaft is rocked during the operation of the machine to communicate an oscillating motion to the sole-support 41 and so to the channeling knife 43. This rocking motion is obtained from a cam-actuated bell-crank-lever 93 (partly seen in Fig. 1) slidably mounted upon the shaft 75 and carrying a pin 95 extending into a recess in an arm 97 formed on the sleeve 73. The construction of the elements just described is quite usual in rounding and channeling machines of the Goodyear type. Commonly in such machines, the sole-support normally occupies an advanced position and is only retracted from the feed-plate by depression of a treadle when it is desired to insert the margin of an outsole to be rounded and channeled. In the present machine, however, it is preferable to arrange the sole-support 41 normally in a retracted position. This result is attained by providing a tension-spring 99 attached at its upper end to a collar 101 fixed on the rod 51 and at its lower end to a hook 103 in the column 59. The strength of the spring is such that it normally serves to overcome the action of the spring 87 and retains the shaft 75 and sole-support 41 in retracted position. This position is controlled by engagement of the hand-lever 65 with an adjustable stop-screw 105 on the frame. The sole-support 41 is only advanced toward the feed-plate 45 to grip the work, when the rod 53 is depressed by its treadle and the rod 51 consequently raised through the lever 55. The arrangement of the machine is such that depression of the rod 53 causes the sole-support 41 and channeling knife 43 to be lowered and the crease-guide 47 raised. The change of position of these parts upon depression of the treadle connected to the rod 53 will be appreciated by comparing Figs. 4 and 5. Mechanism for causing heightwise motion of the channeling knife upon depression of a treadle is old in rounding and channeling machines and is described in detail in the Perry patent. Consequently, this mechanism in the present machine will be but briefly described. The rod 53 has an adjustable collar 107 mounted thereon near its top and below the collar passes freely through a sleeve 109, which is pivoted at one end of a lever 111 carried upon a rock-shaft 113. Such a lever 111 is ordinarily employed in rounding and channeling machines of the Goodyear type, to cause the forepart-guide to be brought into or out of operative position. Since in the present machine the forepart-guide is not necessary, the actual work-engaging portion thereof may be removed, and the movement of its pivoted arm used only to effect the depression of the crease-guide 47. Such depre-

sion may be brought about by engagement of a roll on the arm of the forepart-guide with a plate on the arm of the crease-guide. This is as in the Perry patent. At the end opposite the sleeve 109, the lever 111 carries a roll 117 within a cam-slot 119 in the lower end of a lever 121 fulcrumed on the frame at 123. The upper end of the lever 121 is provided with a guideway 125, in which a pivot-block is secured in adjusted position and is connected by a link 127 with an arm 129 extending downwardly from a rock-shaft 131. This rock-shaft has a rearwardly projecting arm 133 secured thereto and joined by a link 135 and arm 137 to usual mechanism for controlling the carrier-slide 79 and therefore the heightwise position of the sole-support 41 and channeling knife 43. The arrangement is such that turning of the lever 111 in a clockwise direction (Fig. 1) by a depression of the treadle-rod 53 will cause the carrier-slide with the channeling knife to be lowered with respect to the support 77. 5

The form of the channeling knife 43 will be apparent from Figs. 3, 4 and 5. The stem of the knife is secured to the sole-support and has a portion extending upwardly therefrom. The 25 knife bends over forwardly and downwardly and its cutting edge 139 extends more or less vertically and may be about three-eighths of an inch in length, its lower portion extending below and a slight distance outside the top edge of the sole-support. The cutting edge is not quite straight, but is slightly curved to adapt it to make the 30 channeling cut 17, 19 shown in Fig. 7. It has been found preferable to make the rocking movement of the sole-support 41 in the guideway 81 35 rather more restricted than is usual in rounding and channeling machines of the Goodyear type. This may be seen in the length of the slot 85 (Figs. 4 and 5). 30

A portion of a shoe to be operated upon by the 40 machine of this invention is partially shown in Fig. 6 as being upon a last 1 and having an upper 3, an insole 5, a welt 7, an inseam 9, an outsole 11 and bottom-filling 13, the waist-portion of the outsole having already had formed in it an English channel 15 from one end of the breast-line to the other about the forepart. It is presented to the machine of the present invention at one end of the waist at one side of the shoe, as shown in Fig. 4. The flap of the channel 45 formed by the cut 15 will preferably have been opened slightly, to permit the operator so to present the work to the machine that the channeling knife 43 enters readily into the cut. As seen in Fig. 4, before the operator depresses the 50 treadle connected to the treadle-rod 53, the crease-guide 47 occupies such a lowered position that, until it is raised, the channeling knife cannot enter farther into the cut 15, and the outsole margin lies out of the path of the rounding knife 39. The operator now depresses the treadle, raising the rod 51, and the spring 87 is allowed to 55 advance the sole-support 41 against the tread-face of the outsole. The work is thus so held between the crease-guide and feed-plate 45 and the sole-support that the blade of the channeling knife is retained in the cut 15. Upon continued depression of the treadle, when the rod 53 has been moved downwardly sufficiently for the collar 107 to contact with the sleeve 109, the channeling 60 knife is lowered and the crease-guide elevated. The operator will keep the shoe pressed upwardly in engagement with the crease-guide. The parts are now in operating position, as seen in Fig. 5, 65 and the sole-edge is advanced in the path of the 70 75

rounding knife 39, which will trim off the surplus margin as indicated by the line 143 (Fig. 5). At the same time, the channeling knife will deepen the cut already made in the outsole to produce the American form of channel seen in Fig. 3 and will remove a wedge-shaped piece of material from the sole-edge, thus reducing the thickness. When the waist-portion of the outsole at one side of the shoe has been operated upon, the operator will allow the treadle to rise and will remove the shoe, turn it over and operate similarly upon the waist-portion of the outsole at the other side. The effect of the operation will be to transform the English channel previously cut in the waist-portion of the outsole into an American channel and to simultaneously round the outsole and welt. Further, material will have been removed from the waist at each side, so that a desirable thin-edged appearance will be imparted to this portion of the outsole in the finished shoe.

Having described my invention, what I claim as new and desire to secure by Letters Patent of the United States is:

1. The combination with movable shoe-gripping means, of a channeling knife, a rounding knife, and a movable work-guide for normally holding a shoe in position to be acted upon by the gripping means and out of the field of action of the knives.

2. The combination with movable shoe-gripping means, of a channeling knife, a rounding knife, a movable work-guide for normally holding a shoe in position to be acted upon by the gripping means and out of the field of action of the knives, and means arranged to move the gripping means and one of the knives into operating position.

3. The combination with movable shoe-gripping means, of a rounding knife mounted for reciprocation above the gripping means, a movable guide normally engaging the work to hold it below the plane of the rounding knife, and means arranged to elevate the guide to present the work to the rounding knife.

4. The combination with movable shoe-gripping means, of a channeling knife, a rounding knife mounted for reciprocation above the channeling knife, a movable guide normally engaging the work to hold it below the plane of the rounding knife, and means arranged to elevate the guide to present the work to the rounding knife and to move the channeling knife into engagement with the work.

5. The combination with a channeling knife, of normally separated members relatively movable to grip the margin of a sole, a crease-guide arranged initially to position the sole out of engagement with the channeling knife, and means arranged to move the members relatively to grip the sole-margin and to move the channeling knife and crease-guide to cause the engagement of said knife and the sole.

6. In a machine of the class described, movable work-gripping means, a movable channeling knife, and a member movable by the operator to produce movement of the gripping means to grip the work and of the channeling knife into engagement with said work.

7. In a machine of the class described, a movable support by which the work is gripped, a channeling knife mounted thereon, and a member movable by the operator to control the work-gripping movement of the support in one direction and to control the movement by the sup-

port of the knife in another direction into and out of engagement with the work.

8. In a machine of the class described, a movable support by which the work is gripped, a channeling knife mounted thereon, a guide member variable in position, and a member movable by the operator to produce the work-gripping movement of the support, the position of the guide member and the movement by the support of the knife into and out of engagement with the work.

9. In a channeling machine, a channeling knife supported normally out of operating position, a sole-support, a feed member, said sole-support and feed member being constructed and arranged to grasp a sole between them, means for normally maintaining the sole-support away from the feed member, operator-controlled means for moving the knife into operating position, and means for advancing the sole-support toward the feed member to grasp the sole upon movement of the operator-controlled means to move the knife.

10. In a channeling machine, a channeling knife supported normally out of operating position, a support for the tread-surface of the sole of a shoe, an opposite co-operating feed member, a crease-guide positioned normally to maintain the sole out of engagement with the channeling knife, means for normally maintaining the sole-support separated from said feed member, operator-controlled means for moving the knife and the crease-guide in opposite directions into operating positions, and means for advancing the sole-support toward the feed member to grasp the sole upon movement of said operator-controlled means to move the knife, the advancing means being controlled by the operator-controlled means.

11. In a channeling machine, a knife constructed and arranged to cut a channel extending inwardly from the edge of a sole, said knife being supported normally out of operating position, a reciprocating knife for trimming the edge of a sole, a support for the tread-surface of the sole, a feed member engaging a marginal surface of the shoe opposite the sole, a crease-guide positioned normally to maintain the sole out of engagement with the channeling knife and out of the path of the trimming knife, operator-controlled means for moving the channeling knife and the crease-guide in opposite directions into operating positions, said crease-guide when in operating position serving to so locate the shoe as to control the depth of the channel cut by the channeling knife and the extent to which the sole-margin is reduced by the trimming knife, and means for advancing the sole-support toward the feed member to press the work against said feed member, said means being made effective upon movement of the operator-controlled means to move the knife and the crease-guide into operating positions.

12. In a machine of the class described, a rounding knife, a feed-plate, a sole-support movable toward and from the feed-plate, a channeling knife carried by the support, a spring acting upon the support to move it toward the feed-plate, and a spring stronger than such support-spring for moving the support away from the feed-plate.

13. In a machine of the class described, a feed-plate, a sole-support movable toward and from the feed-plate, a channeling knife carried by the support, a spring acting upon the support to move it toward the feed-plate, a rod movable by

the operator to allow the spring to act, and a spring connected to the rod and exerting upon the support a force greater than that of the previously mentioned spring.

5 14. In a machine of the class described, a feed-plate, a carrier movable toward and from the plate, a sole-support movable upon the carrier, a channeling knife mounted upon the support, and a member for actuation by the operator 10 to both move the carrier and the support upon the carrier.

15. In a machine of the class described, a feed-plate, a rounding knife, a carrier movable toward and from the plate, a sole-support movable upon 15 the carrier toward and from the rounding knife, a channeling knife mounted upon the support, a treadle-rod arranged to move the support upon the carrier, a rod arranged to control movement of the carrier, and connections between the rods 20 to cause them to act successively.

16. In a machine of the class described, a feed-plate, a rounding knife, a carrier movable toward and from the plate, a sole-support movable upon the carrier toward and from the rounding knife, 25 a channeling knife mounted upon the support, a treadle-rod arranged to move the support upon the carrier, a rod arranged to control movement

of the carrier, and connections between the rods to first permit movement of the carrier and thereafter to cause the movement of the support upon the carrier.

5 17. In a machine of the class described, a feed-plate, a reciprocatory rounding knife, a carrier movable toward and from the plate, a sole-support movable upon the carrier toward and from the rounding knife, a channeling knife mounted upon the support, a treadle-rod arranged to move 10 the support upon the carrier, a rod arranged to control movement of the carrier, and a lever connected to the carrier-rod and moved by the treadle-rod.

18. In a machine of the class described, a feed-plate, a reciprocatory rounding knife, a carrier movable toward and from the plate, a sole-support movable upon the carrier toward and from the rounding knife, a channeling knife mounted upon the support, a treadle-rod arranged to move the support upon the carrier, a rod arranged to control movement of the carrier, a lever connected to the support-rod and moved by the treadle-rod, and a spring acting upon the carrier-rod to maintain the support normally 25 separated from the feed-plate.

CHARLES MARTIN BAGSHAW.
